UNITED STATES PATENT OFFICE.

CHARLES MAURICE PHILIPPE MONTBARBON, OF PARIS, FRANCE.

MEANS FOR REGULATING THE SUPPLY OF ELECTRIC CURRENTS.

No. 896,227.

Specification of Letters Patent.

Patented Aug. 18, 1908.

Application filed April 18, 1907. Serial No. 368,849.

To all whom it may concern:

Be it known that I, CHARLES MAURICE PHILIPPE MONTBARBON, of 135 Rue de Tolbiac, Paris, France, engineer, have invented 5 a new and useful Improvement in Means for Regulating the Supply of Electric Currents, which improvement is fully set forth in the following specification.

My invention relates to improvements in 10 means for regulating the supply of current from generators, such as magnetos, dynamos, or the like.

The object of the invention is to provide a simple means by which the use of platinum 15 screws, cams, tremblers, rollers, collectors, and the like may be avoided, while at the same time the apparatus can be easily removed for repairs or cleaning.

An essential feature of applicant's device 20 is that the current is never interrupted, thus avoiding the injurious effects of self-induction.

My invention is particularly advantageous 25 for the distribution of current from a generator to the primary of an induction coil, since by means of it, two induction currents are produced in the secondary at each passage of the brush onto and off a contact, as will be clear from the description hereinafter.

30 These results are obtained by connecting the insulated end of the armature winding to a brush which rotates with it and which normally rests against grounded contact plates arranged in the form of a ring by which the

35 armature is short circuited when current is not to be delivered, while the passage of the brush over two insulated terminals places it in series with the circuit to which current is to be delivered, for example, the primary of a transformer. 40 The shape of these terminals is such that in its movement the brush never breaks the circuit of the armature, thus avoiding any possibility of damage from self-induction. This arrangement is applicable to all 45 apparatus for periodically allowing the passage of an electric current.

The annexed drawing illustrates one form in which this invention may be embodied.

Figure 1 shows diagrammatically the arrangement as seen at the end of the armature spindle; Fig. 2 is a section; Fig. 3 shows a portion of the insulated contacts; and Fig. 4 shows a modification.

One end *a* of the armature winding is connected to the spindle *b* and through it to ground in any usual manner. The other end

c, carefully insulated, passes out from the spindle through a central hole and is connected to a metal piece *d*, embedded in the insulating disk *e*, which is keyed upon the 50 spindle. In a cavity in the piece *d* is mounted a brush *f* of carbon or metal, pushed outwards by a spring *g*. The brush rubs upon the inside of a stationary ring, comprising two contact plates *i j* grounded in any suitable way, as for example, by the conductors *m* connected to earth at *n*, said contact plates being separated by insulated terminals *k l* connected to one end of the circuit to which current is to be delivered, for example, 65 the primary of an induction coil, the other end of the circuit being connected to ground.

Figs. 3 and 4 which show partial developments of the internal face of the ring, illustrate the shape the terminals may be given 70 in order to prevent the interruption of the armature current by the passage of the brushes from the contact plate to the terminal and vice versa, which would cause a spark and would be very prejudicial by reason of the self-induction of the armature, which is generally high. This arrangement has further the great advantage of equalizing 75 the wear of the insulation and the conducting parts as the continuity of the surface on 80 which the brush rests is never broken.

Having thus fully described my invention, what I claim is:—

1. The combination, with a generator having an armature, one terminal of which is 90 grounded, of a ring comprising grounded contact-plates and terminal plates alternating with and insulated from each other, and a contact device connected to the other terminal of the armature and arranged to make 95 a traveling contact with the plates comprising the ring.

2. The combination, with a generator having an armature, one terminal of which is grounded, of a ring comprising grounded contact-plates and terminal plates alternating with and insulated from each other, said contact and terminal plates having their adjacent ends lapping past each other, and a contact device connected to the other terminal 100 of the armature and arranged to make a traveling contact with the plates comprising the ring.

3. The combination, with a generator having an armature, one terminal of which is 110 grounded, of a ring comprising grounded contact-plates and terminal-plates alternating

2

with and insulated from each other, said contact-plates having their adjacent endslapping past each other, a contact device connected to the other terminal of the armature 5 and arranged to make a traveling contact with the plates comprising the ring, and an induction coil having its primary connected to the terminal plates of the ring.

4. The combination, with a generator having a rotating armature, one terminal of which is grounded, of a ring comprising grounded contact plates and terminal plates alternating with and insulated from each other, a contact device connected to the 10 other terminal of the armature and rotating with said armature, said contact device traveling in contact with the plates comprising the ring, and a work circuit connected to the terminal plates. 15

5. The combination, with a generator having a rotating armature, one terminal of which is grounded, of a ring comprising grounded contact plates and terminal plates alternating with and insulated from each other, said contact plates having their adjacent endslapping past each other, a contact device connected to the other terminal of the armature and rotating with said armature, 20 said contact device traveling in contact with the plates comprising the ring, and a work circuit connected to the terminal plates. 25

In testimony whereof I have signed this specification in the presence of two subscribing witnesses.

CHARLES MAURICE PHILIPPE MONTBARBON.
